CLAIM

The ornamental design for a record player, as shown and described.

DESCRIPTION

FIG. 1 is a front perspective view of a record player showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is another front perspective view thereof;

FIG. 9 is rear perspective view thereof;

FIG. 10 is a bottom perspective view thereof, showing the record player in a closed state of use; and,

FIG. 11 is an enlarged view of the record player taken from the circle part in FIG. 7.
